Primary Examiner — Joseph Kukella*Assistant Examiner* — Arva P Adams(74) *Attorney, Agent, or Firm* — Leason Ellis LLP(57) **CLAIM**

The ornamental design for a stem glass, as shown and described.

DESCRIPTION

FIG. 1 is a top-front isometric view of a rotationally symmetric stem glass according to our new design;

FIG. 2 is a bottom-front isometric view thereof;

FIG. 3 is a top plan view thereof;

FIG. 4 is a bottom plan view thereof;

FIG. 5 is a front view thereof, the rear and side views being rotationally symmetric; and,

FIG. 6 is a cross-sectional outline of the front view thereof taken along line 6-6 of FIG. 5.

Conventional shading is illustrated for purposes of highlighting the line drawings, but forms no part of the claimed design.

The cross-sectional view reveals a thickness of the glass and stem as well as interior and exterior contours.
